[57] CLAIM

The ornamental design for a digital wrist watch, or the like, substantially as shown and described.

DESCRIPTION

FIG. 1 is a top plan view of a digital wrist watch or the like showing my new design;
 FIG. 2 is a right side elevational view thereof, the left side being similar but without the buttons;
 FIG. 3 is a bottom plan view thereof;
 FIG. 4 is a front elevational view thereof;
 FIG. 5 is a rear elevational view thereof;
 FIG. 6 is a top plan view of a second embodiment of my new design of FIGS. 1-5;
 FIG. 7 is a left side elevational view thereof, the right side being similar but without the buttons;
 FIG. 8 is a top plan view of a third embodiment of my new design of FIGS. 1-5;
 FIG. 9 is a right side elevational view thereof;
 FIG. 10 is a left side elevational view thereof;
 FIG. 11 is a top plan view of a fourth embodiment of my new design of FIGS. 1-5;
 FIG. 12 is a front elevational view thereof;
 FIG. 13 is a right side elevational view thereof;
 FIG. 14 is a top plan view of a fifth embodiment of my new design of FIGS. 1-5;
 FIG. 15 is a front elevational view thereof;
 FIG. 16 is a right side elevational view thereof.
 Each bottom view of the modified forms is the same as FIG. 3, but with the appropriate button arrangement being understood.
